2,450,976

DUST ARRESTER FOR BLAST FURNACES

Reuben M. McKelvey, Johnstown, Pa.

Application October 3, 1945, Serial No. 620,101

3 Claims. (Cl. 266—31)

1

The invention relates to a blast furnace salvaging attachment or top, and more especially to a stock salvaging and safety device for a forced draft stack or bleeder of shaft or blast furnaces.

The primary object of the invention is the provision of a device of this character, wherein on installation there will be a salvaging of approximately 95% of material otherwise lost in blast furnaces, eliminating cleaning up labor expense and resultant shutting down of the furnaces for this cleaning operation, and an increase in production.

Another object of the invention is the provision of a device of this character, wherein safety is assured from falling material due to explosions, and the life of the stack is materially increased, as well as a reduction in repair expense thereto.

A further object of the invention is the provision of a device of this character, wherein the clogging of a stack is avoided, and damage thereto eliminated or reduced to a minimum.

A still further object of the invention is the provision of a device of this character, which is simple in construction, thoroughly reliable and efficient in operation, strong, durable, automatic in the working thereof, possessed of few parts, thus economical in repairs, readily accessible for replacements, and inexpensive to manufacture and install.

With these and other objects in view the invention consists in the features of construction, combination, and arrangement of parts as will be hereinafter more fully described, illustrated in the accompanying drawing, which discloses the preferred embodiment of the invention, and pointed out in the claims hereunto appended.

In the accompanying drawing, the view is an elevation, partly broken away, of the device constructed in accordance with the invention.

Referring to the drawing in detail, A designates generally the blast furnace top constructed in accordance with the invention, and comprises a dome-like head 10, having upstanding off-set stacks 11 rising therefrom and communicating with the off-takes 12 of the head 10, while intermediate with relation to the rise of these stacks 11 is a receiving tank or drum 13 having the bracket connections 14 with such stacks, which are vertically aligned and in parallelism with each other.

Crowning the uppermost open ends of the stacks 11 are substantially concave-convex shaped caps 15 having communication with upwardly divergent funnels 16, each tapering in a downward direction following the incline disposition thereof,

2

and open into a coupling union 17 of the tank or drum 13 centrally thereof at its top. This union 17 below the points of communication of the funnels 16 therewith and interiorly thereof effects a valve seat 18 for shaped valve 19, which is normally open to receive material and adapted to be closed when bell shaped valve 26 is opened to discharge material from the tank 13 to the furnace thereby preventing heat and gases from escaping. Therefore valve 26 is counterweighted and normally closed while valve 19 is normally open. The funnels 16 at their uppermost larger ends are provided with outlets 20 protected by storm guards 21 overhanging the same.

15 The tank or drum 13 at its bottom is provided with a hopper 22 which has a central valve seat 23 for a flue 24 forming a discharging spout leading exteriorly of the furnace, so that material collected within the tank or drum 13 can 20 be dispensed therefrom through such spout in the working of the device A.

Engaging the seat 23 within the nipple 23 is a bell shaped valve 26 counterweighted at 27.

25 The uppermost open ends of the stacks 11 have associated therewith flap like baffles 28 which are confined within the caps 15, as will be clearly apparent from the drawing. The baffles 28 are normally seated and are unseated by furnace pressure.

30 In the working of the device it will salvage about 95% of material otherwise lost if used in connection with a blast furnace, and results in about 95% saving of lost material; 100% safety from falling material; 90% of clean up labor, and 35 30 to 50% increased production, this being effected by saving in shutdowns to clean up materials that otherwise are deposited on the furnace tops and surrounding spaces thereto. The device is usable on any force draft stack that throws out 40 materials. The essence of the device is to have the escaping materials hit the stack caps and be directed downward into the funnels and to the tank or drum, while at the same time pressure is reduced by expansion and allowed to escape from 45 the stack caps and over the funnels.

What is claimed is:

1. A device of the kind described, comprising a plurality of furnace top stacks, a receiving tank intermediate of the stacks, funnels establishing communications between the stacks and tank, caps crowning the communications between the stacks and funnels and having escape outlets, flap-like baffles at the tops of said stacks confined within said caps, a discharging spout leading from the tank, and valves controlling communica-

50 55

tions between the funnels and the tank and the latter and the spout respectively.

2. A device of the kind described, comprising a plurality of furnace top stacks, a receiving tank intermediate of the stacks, funnels establishing communications between the stacks and tank, caps crowning the communications between the stacks and funnels and having escape outlets, flap-like baffles at the tops of said stacks confined within said caps, a discharging spout leading from the tank, valves controlling communications between the funnels and the tank and the latter and the spout respectively, storm guards for the escape outlets, and means counterweighting the valve controlling the communication between the tank and the spout.

3. A device of the kind described, comprising a plurality of furnace top stacks, a receiving tank intermediate of the stacks, funnels establishing communications between the stacks and tank, caps crowning the communications between the stacks and funnels and having escape outlets,

5

flap-like baffles at the tops of said stacks confined within said caps, a discharging spout leading from the tank, valves controlling communications between the funnels and the tank and the latter and the spout respectively, storm guards for the escape outlets, and means counterweighting the valve controlling the communication between the tank and the spout.
